CLAIM

The ornamental design for a meat thermometer, as shown and described.

DESCRIPTION

FIG. 1 is a top perspective view of a meat thermometer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view.

1 Claim, 8 Drawing Sheets
